UNITED STATES PATENT OFFICE.

JOHN A. KEARNEY, OF NEWARK, NEW JERSEY, ASSIGNOR TO GILLIS & GEOGHEGAN, OF NEW YORK, N. Y., A FIRM.

HOISTING APPARATUS.

1,101,190.

Specification of Letters Patent. Patented June 23, 1914.

Application filed January 30, 1913. Serial No. 745,065.

To all whom it may concern:

Be it known that I, JOHN A. KEARNEY, a citizen of the United States, residing at Newark, in the county of Essex and State 5 of New Jersey, have invented a certain new and useful Improvement in Hoisting Apparatus, of which the following is a specification.

The invention is based on an apparatus 10 shown and described in Letters Patent to Louis O. Forman, dated April 30, 1912, No. 1,024,885, and the object of the present invention is to increase the efficiency of the previous apparatus by providing improved 15 means for lifting and depositing the load to be handled.

The invention consists in certain novel 20 features of construction and arrangement by which the above object is attained, to be hereinafter described and pointed out in the claims.

The accompanying drawings form a part 25 of this specification and show the improved apparatus.

Figure 1 is an elevation, partly in vertical section, showing in full lines the apparatus extended for service, and in dotted lines the position assumed when partly collapsed. Fig. 2 is a plan or top view of the crane-arm 30 or jib and its immediately connected parts. The remaining figures are on a larger scale and show parts of the apparatus. Fig. 3 is a vertical section taken on the line 3—3 in Fig. 2, and partly in elevation. Fig. 4 is an 35 elevation of a portion carrying the winding or hoisting mechanism. Fig. 5 is a corresponding vertical section, partly in elevation, taken on the line 5—5 in Fig. 4. Fig. 6 is a plan view of the winding mechanism, 40 partly in horizontal section, the plane of section being indicated by the line 6—6 in Fig. 1. Fig. 7 is an elevation, partly in vertical section on the line 7—7 in Fig. 6, showing the brake. Fig. 8 is a plan view of the 45 elevating mechanism, partly in horizontal section taken on the line 8—8 in Fig. 1.

Similar letters of reference indicate the same parts in all the figures.

A is a hollow post firmly set and supported 50 in a suitable pit or hoistway below the street level, telescopically inclosing a tubular standard B in which is secured a core B¹ having a rack B² with its teeth presented to a long slot b extending vertically of the 55 standard. In the upper part of the post is

a similar but short slot a registering with the slot b and permitting the rack to be engaged by a toothed rack-wheel C¹ mounted on a shaft C supported in a two-part yoke D clamped upon the post. The shaft C also carries a gear-wheel C² in mesh with a pinion C³ on a shaft C⁴ which latter is extended horizontally and squared to receive a crank L by which the gears and rack wheel may be turned and the standard thus raised 60 or lowered. A pawl D¹ mounted on the yoke and engaged with the teeth of the rack-wheel C¹ serves to support the standard in the elevated position, and a pin A³ thrust transversely through the post beneath the 65 standard holds the latter in the fully elevated position, as described in the Letters Patent above referred to.

At the upper end of the standard is a coupling B³ screwed thereon and receiving 70 the screw-threaded lower end of an extension-piece B⁴ in axial alinement with the standard, serving as a support or vertical shaft for the vertical body portion of a T-shaped connection K loosely mounted on 75 the extension-piece to swing horizontally and carrying in its horizontal branch a tubular crane-arm or jib K¹ extending at a right angle from the standard and having a pulley K² mounted in slots in its outer end. 80 The upper face of the coupling B³ and adjacent face of the T-connection are provided with annular race-ways containing a series of antifriction balls K³, and the upper face of the T is similarly grooved to receive 85 a series of balls K⁴ applied between the T and a cap B⁵ screwed upon the upper end of the extension-piece B⁴, closing its upper end and serving as an adjusting means for 90 the two sets of ball-bearings. A plate B⁶ secured upon the cap by a bolt B⁷ has angularly extending horizontal arms B⁸ provided with holes adapted to receive the hooked ends of rods B⁹ B⁹ secured to the 95 wall of the building, not shown, above the sidewalk level and serving as braces for the upper end of the standard as will be understood. Thus arranged the arm or jib K¹ may be easily turned to extend over the hoistway in raising a load, and swung over 100 the sidewalk to deposit the load thereon or upon a suitable truck placed to receive it.

Inclosing the standard above the post and below the T is a sleeve E having an outwardly projecting annular flange on its 110

lower end, carrying a hollow collar F encircling the sleeve and held thereon by a threaded collar or nut E² screwed upon the upper end of the sleeve. Race-ways are cut in the upper face of the flange E¹ and the lower face of the collar to receive a series of antifriction balls E³ serving to permit the collar and its connected parts to rotate or swing horizontally on the sleeve.

10 The sleeve E is held to the standard B by a pin E⁴ mounted in a housing E⁵ on the flange E¹ and thrust inwardly by a spring E⁶ to engage a hole b¹ in the standard. A cross-handle E⁷ on the projecting end of the pin facilitates withdrawal when required, and to guard against accidental disengagement an arm or bracket F¹ is mounted on the collar F above the housing E⁵ adapted to receive an end of the handle when the latter is given a quarter turn and hold the pin E⁴ against outward movement until the handle is again released. The collar F is part of a horizontal frame comprising the outwardly extending arms F² carrying the winding mechanism.

15 G is a shaft mounted in the arms and carrying a pinion G¹ in mesh with a gear-wheel H¹ mounted on a second shaft H parallel with the shaft G, and carrying a winding-drum or spool H² on which the hoisting cable J is wound. The latter is preferably a light wire rope extending from the drum H² to and over the pulley K² and provided at its free end with a hook J¹ or other suitable grapple adapted to engage the load.

20 The pinion G¹ is provided with a holding pawl F⁸, and in order to control the lowering of the load a brake-drum G³ is mounted on the shaft G, having a brake-band N of steel partially inclosing the drum and connected at the ends to pins N¹ N² in a lever N⁴ pivotally mounted at N³ on the underside of one of the arms F². The inner face of the band N in contact with the drum carries a strip N⁵ of brake-lining adapted to insure the strong frictional contact required.

25 An overhung end of the shaft G is squared as at G² to receive a crank L¹ by which the winding mechanism may be rotated.

30 To hold the collar F and its arms in the desired position on the sleeve a pin F⁴ is employed similar to the pin E⁴ above described; it is mounted to slide in a housing F⁶ and is thrust inwardly into engagement with a hole e in the sleeve by the force of a spring F⁶. When the pin F⁴ is withdrawn by the handle F⁷ the collar and its winding mechanism may be swung in either direction horizontally, and the pin again engaged in a corresponding hole, not shown, to present the winding mechanism for convenient operation.

35 In collapsing the apparatus from the elevated condition in Fig. 1, the rods B⁹ B⁹ are detached, the pin A⁸ removed and the stand-

ard lowered by the crank L until the collar F reaches the top of the post A, the latch-pin A⁴ is then withdrawn and the standard further lowered, sliding freely through the collar, until the coupling B³ rests upon the upper face of the collar E². The jib K¹ may be swung into any convenient position. A reversal of the operation raises the standard B, the arm or jib K¹ rising above the collar until the latch-pin E⁴ engages and lifts the winding mechanism as will be understood. The arrangement permits the winding mechanism to be located at a convenient height above the sidewalk for easy operation while the jib K¹ is enough higher to allow the load to be swung clear and deposited at any point within the range of the apparatus.

I claim:

1. In an apparatus of the character set forth, a hollow post, a standard arranged to slide telescopically therein, a jib at the upper end of said standard, mechanism for raising and lowering said standard in said post, a collar loosely inclosing said standard with liberty for the latter to slide therethrough, winding mechanism carried by said collar, and means for detachably engaging said collar with said standard.

2. In an apparatus of the character set forth, a hollow post, a tubular standard arranged to slide telescopically therein and having a vertical slot on one face, a jib at the upper end of said standard, a rack in said standard with its teeth presented to said slot, mechanism on said post constructed to engage said rack through said slot and to raise and lower said standard, a sleeve loosely inclosing said standard above said post, a flange on said sleeve, a collar loosely inclosing said sleeve and carrying hoisting mechanism, a collar above said collar and engaged with said sleeve, a series of antifriction balls between said collar and flange, means carried by said collar for detachably engaging said collar with said sleeve, and means for detachably engaging said sleeve with said standard.

3. In an apparatus of the character set forth, a vertically movable standard, a coupling on the upper end of said standard, an extension-piece in said coupling forming a continuation of said standard, a T having its vertical body portion loosely inclosing said extension-piece, a cap on the latter, and a jib carried by the horizontal branch of said T.

4. In an apparatus of the character set forth, a vertically movable standard, a coupling on the upper end of said standard, an extension-piece in said coupling forming a continuation of said standard, a T having its vertical body portion loosely inclosing said extension-piece, a cap on the latter, a series of antifriction balls between said T and coupling, a series of antifriction balls

between said **T** and cap, and a jib carried by the horizontal branch of said **T**.

5. In an apparatus of the character set forth, a vertically movable standard, a coupling on the upper end of said standard, an extension-piece in said coupling forming a continuation of said standard, a **T** having its vertical body portion loosely inclosing said extension-piece, a cap on the latter, a

10 jib carried by the horizontal branch of said **T**, a plate on said cap having arms adapted to support detachably engaged rods arranged to serve as braces for said standard.

6. In an apparatus of the character set 15 forth, a vertically movable standard, a jib at the upper end of said standard, mechanism for raising and lowering said standard in said post, a sleeve loosely inclosing

said standard above said post, a flange on said sleeve, a spring-pin in said flange arranged to engage in a hole in said standard, a cross-handle for said pin, a collar loosely inclosing said sleeve and carrying hoisting mechanism, a collar on said sleeve above said collar, and a projecting arm on said collar 25 adapted to serve with said cross-handle and prevent withdrawal of said pin from said hole.

In testimony that I claim the invention above set forth I affix my signature, in 30 presence of two witnesses.

JOHN A. KEARNEY.
